US00D788913S

(12) **United States Design Patent** (10) **Patent No.:** **US D788,913 S**
(45) **Date of Patent:** **** Jun. 6, 2017**

(54) **NASAL DILATOR DEVICE**

(71) Applicant: **ASAP BreatheAssist Pty Ltd**, Victoria (AU)

(72) Inventors: **Elizabeth Jane Pepper**, Victoria (AU); **Michael Ralph Burgess Johnson**, Victoria (AU); **Justin Robert Armistead**, Victoria (AU); **Toby James Hartley**, Victoria (AU)

(73) Assignee: **ASAP BREATHEASSIST PTY LTD**, Victoria (AU)

(**) Term: **15 Years**

(21) Appl. No.: **29/531,291**

(22) Filed: **Jun. 24, 2015**

(30) **Foreign Application Priority Data**

Jan. 30, 2015 (AU) 10495/2015

(51) **LOC (10) Cl.** **24-02**

(52) **U.S. Cl.**

(57) **CLAIM**

The ornamental design for a nasal dilator device, as shown and described.

DESCRIPTION

FIG. 1 is an isometric front view of a nasal dilator device in an open configuration in accordance with the invention; FIG. 2 is a top plan view of the nasal dilator in the open configuration;

FIG. 3 is a bottom plan view of the nasal dilator in the open configuration;

FIG. 4 is a front elevation view of the nasal dilator in the open configuration;

FIG. 5 is a rear elevation view of the nasal dilator in the open configuration;

FIG. 6 is a left side elevation view of the nasal dilator device in the open configuration;

FIG. 7 is a right side elevation view of the nasal dilator device in the open configuration;

FIG. 8 is an isometric front view of a nasal dilator device in a closed configuration in accordance with the invention;

FIG. 9 is a top plan view of the nasal dilator in the closed configuration;

FIG. 10 is a bottom plan view of the nasal dilator in the closed configuration;

FIG. 11 is a left side elevation view of the nasal dilator device in the closed configuration; and,

FIG. 12 is a right side elevation view of the nasal dilator device in the closed configuration.
